UNITED STATES PATENT OFFICE

EDGAR WILLEMS, OF CHENES-BOUGERIES, GENEVA, SWITZERLAND

MOVABLE KEY DEVICE FOR MUSICAL INSTRUMENTS HAVING KEYS

Application filed August 20, 1932, Serial No. 629,567, and in Switzerland August 1, 1932.

The object of the present invention is a movable key device for musical instruments having keys, such as pianos or harmoniums for example.

5 The aim of this device is to allow the musical development of the ear, by enabling cords and intervals to be formed on musical instruments having keys, without their being known beforehand, in such a way that it is necessary to guess them by means of the ear.

10 The principal object of the invention is a device of this kind established in such a way that the keys of the device hide the keys of the instrument, said keys of the device being arranged to correspond to the keys of the instrument, all being placed at the same height and at the same distance apart, having the same length and the same colour, in 15 such a way that it would be impossible to recognize, by sight or by touch, which key of the instrument is situated under any given key of the device placed on the keyboard of the instrument.

20 25 The annexed drawing represents, by way of example, one form of execution of the device according to the invention.

Figs. 1, 2 and 3 are respectively a longitudinal vertical section view of the device, 30 passing through the line I—I of Fig. 3, a lateral elevation, and a plan.

Figs. 4 and 5 are transverse vertical section views through the lines IV—IV, V—V of Fig. 1.

35 Figs. 6 and 7 are a front view and an end view, respectively, of a block serving for striking several cords at once.

This form of execution comprises a rectangular frame *b* constituting the support mentioned in the introduction, made of a sheet of metal, the side of which presents upper horizontal and inclined surfaces and lateral vertical surfaces. Its small sides comprise, in the inside, blocks *a*, of wood for 40 example, intended to rest on the keyboard of the instrument and furnished with coverings *c*, in cloth for example.

The blocks *a* present, near one of their ends, recesses *d* in which lies a cylindrical metal rod *e*. It is furnished with keys *f*, *g*,

made of wood, and painted all in black for example, arranged side by side, able to turn on the rod, separated one from the other and from the small sides of the frame by metal rings *h*. The keys *f*, intended to rest upon the black notes of the instrument, are composed solely of a body *i*, the keys *g*, which come to bear upon the white notes, being composed of a body *i* and a lower projection *j*. The bodies *i* of all the keys *f*, *g* are 55 identical the one with the other as regards their form, colour, position and arrangement on the rod *e*: they have the form of upright prisms with rectangular bases, nevertheless presenting an inclined plane *k* 60 on their upper surface. The projections *j* have also the form of upright prisms with rectangular bases and are integral with the bodies *i*. The distances between the various 65 keys are equal.

The metal sheet *b* extends into the inside of the frame on the two long sides of this latter, in *l* and *m*, it hides the two ends of various keys and forms a rectangular window *n* through which the middle portions 70 only of the keys appear. The coverings *o*, *p*, in cloth for example, are fixed to the parts *l*, *m* and limit the rotary movement of the keys *f*, *g* in both directions.

75 The form of execution described is employed as follows:

It is placed on the keyboard of the instrument, of a piano for example, in such a way that its keys *f* rest upon the black notes of the instrument, and its keys *g* on the white 80 notes. Thanks to the precautions taken, all its keys *f*, *g*, are of the same height, the same width and the same colour, and separated one from the other by the same distance; they hide the keys of the keyboard. 85 It is therefore not possible to know by means of the eye or the touch which keys of the keyboard are situated under such and such a key of the device.

If, under these conditions, a cord or an interval is struck, the ear alone can determine what notes have been touched, without being guided or helped by any sensation of touch or sight.

The cords or intervals may be struck di- 100

rectly with the hand or use may be made of flat straight blocks *o* (Fig. 6 and 7) presenting lower projections *p* which enable several notes to be struck at the same time, these 5 projections *p* being situated at a given distance apart; the nature of the cord or interval may be indicated on the lower surface of the corresponding block.

The frame, and the arrangement of the 10 keys in this latter, may differ from that indicated.

What I claim and desire to secure by Letters Patent is:—

1. Movable key device for musical instruments having keys, for the musical development of the ear, intended to be placed on the keys of the instrument and comprising a support on which the keys are arranged, the said keys hiding the notes of the instrument, having the same height, the same length, the same colour and being situated at the same 20 distance one from the other, each forming an intermediary by which the note of the instrument situated underneath the key of the 25 device may be struck.

2. Movable key device for musical instruments having keys, for the musical development of the ear, intended to be placed on the keys of the instrument and comprising a 30 support on which the keys are arranged, the said keys hiding the notes of the instrument, having the same height, the same length, the same colour and being situated at the same distance one from the other, these keys comprising identical bodies, those intended to come to bear upon the white notes of the instrument further presenting a lower projection intended to maintain them at the same height as the other keys resting on the black 35 notes of the instrument when the device is 40 placed on the keyboard.

3. Movable key device for musical instruments having keys, for the musical development of the ear, intended to be placed on the 45 keys of the instrument and comprising a support on which the keys are arranged, the said keys hiding the notes of the instrument, having the same height, the same length, the same colour and being situated at the same 50 distance one from the other, these keys being arranged on a common member around which they can turn and separated from each other by rings also borne by this member, the latter resting in a support in the form of a metal 55 frame.

4. Movable key device for musical instrument having keys, for the musical development of the ear, intended to be placed on the keys of the instrument and comprising a 60 support on which the keys are arranged, the said keys hiding the notes of the instrument, having the same height, the same length the same colour and being situated at the same 65 distance one from the other, these keys being arranged on a common member around which

they can turn and separated from each other by rings also borne by this member, the latter resting in a support in the form of a metal frame, this latter hiding the two ends of the various keys of the device.

5. Movable key device for musical instruments having keys, for the musical development of the ear, intended to be placed on the keys of the instrument and comprising a support on which the keys are arranged, the said keys hiding the notes of the instrument, having the same height, the same length, the same colour and being situated at the same distance one from the other, these keys being arranged on a common member around which they can turn and separated from each other by rings also borne by this member, the latter resting in a support in the form of a metal frame, this latter being furnished with non-metal parts by means of which it comes to bear upon the keyboard of the instrument on which it is desired to place the device.

6. Movable key device for musical instruments having keys, for the musical development of the ear, intended to be placed on the keys of the instrument and comprising a support on which the keys are arranged, the said keys hiding the notes of the instrument, having the same height, the same length, the same colour and being situated at the same distance one from the other, these keys being arranged on a common member around which they can turn and separated from each other by rings also borne by this member, the latter resting in a support in the form of a metal frame, this metal frame presenting non-metal coverings intended to limit the movement of the keys of the device in both directions of rotation.

In testimony whereof I have affixed my signature.

EDGAR WILLEMS.
